COAT FRONT STRUCTURE AND METHOD OF
MAKING THE SAME

Albert M. Kranefuss, Boston, Mass.

Application January 10, 1933, Serial No. 651,027

5 Claims. (Cl. 139—407)

This invention relates to interlining fabrics and more particularly, to a coat front structure which is adapted to be interposed as a stiffening piece in the interior of men's coats between the inner-
5 most lining and the facing and outer cloth of the coat.

Heretofore, practically all of the coat fronts offered to the trade or as constructed by tailors, consist essentially of a woven fabric woven from 10 linen thread, jute, cotton thread, or cotton and jute. Upon the breast of these coat fronts, there is usually stitched a stiffening piece, called hymo or hair cloth, consisting of a filling of resilient wool or stiff hair and cotton warp threads. This 15 hymo or hair cloth is very often not smooth and is apt to curl or buckle when stitched and does not work well under the tailor's iron, during a pressing operation. Frequently, upon the hymo or hair cloth, there is placed a layer of white cot-
20 ton felt, to cover the roughness of the hair felt, and the felt is stitched thereto. This form of coat front has been employed for many years and still is the principal structure employed today.

In order to obviate the difficulties inherent in 25 the structures of the prior art, this invention seeks to overcome them by providing a woven fabric, suitable to be offered to the trade in bolts or pieces, said fabric containing at intervals throughout its length, portions which are more 30 stiff than other surrounding portions of the fabric. The surrounding portions are more flexible or pliable and connect the stiffer portions. The main body of the fabric, the stiff portions and the flexible or pliable portions are all woven at one 35 and the same time.

More specifically, the objects of my invention are attained by weaving a compound fabric having a continuous warp of soft threads such as 40 linen, jute, or cotton and jute and a plurality of alternating sections of weft of soft threads such as linen, jute, or cotton and jute and between these alternating sections just referred to are woven sections of weft consisting of soft threads and relatively stiffer threads. The soft 45 threads of the latter weft sections consist of linen, jute, or cotton and jute and the stiffer threads consist of resilient wool threads or animal hairs, such as goat hairs or horse hairs. Spaced across the width of the fabric and lying within the limits 50 of the weft section just referred to are stiff sections and flexible or pliable sections, the stiff sections being spaced apart by the flexible or pliable sections. The stiff section, by a process of weaving may assume the general shape and area 55 denoting a coat front structure.

Referring to the drawings,

Figure 1 is a portion of the woven fabric so chosen as to represent the weft sections which recur throughout the length of the fabric;

Figure 2 is a cross section of the fabric, taken 60 on line 2—2 of Figure 1; and

Figure 3 is another cross section of the fabric, taken on line 3—3 of Figure 1.

The fabric, shown in Figure 1, is woven so as to be of a width ranging between twenty-four 65 and twenty-seven inches and of a length ranging between fifty and one hundred yards to the bolt. The length is immaterial, since this is dictated by the demands of the trade.

While it is immaterial so far as the finished 70 cloth is concerned which threads are warp and which are filler, for convenience in disclosure the vertically arranged threads shown will be referred to as warp threads while the horizontally arranged threads will be referred to as filler or 75 weft threads.

The warp threads 4 consist of linen, jute, or cotton and jute threads and are soft and are the same throughout the running length of the fabric. These warp threads are formed into the 80 usual shed of warp threads in a manner well known in the art. It will be noted that there are recurring weft sections 1, of a width denoted by the bracket A, said weft sections alternating with other weft sections throughout the length of the 85 fabric. The weft threads 5, in section 1 are soft, being composed of linen, jute, or cotton and jute. The customary weaving process is carried out, that is, each weft thread 5 is woven over and under each thread to the warp, thereby producing 90 a very flexible section of fabric. So much of the fabric is already well known in the art. The weft section denoted by the bracket A is usually twenty-two inches in length.

Coming now to the gist of the invention, it 95 will be noted that there are recurring weft sections denoted by the areas within the brackets B, said weft sections consisting of sections 2 and 3. These weft sections alternate with the weft sections 1. Section 2, in outline, denotes a coat front 100 structure which is very stiff, being woven by having resilient wool weft threads or horsehair weft threads 6 interspersed between the soft weft threads 5, said woolen weft threads or horsehair threads being woven over and under each thread 105 to the warp within the confines of the section 2, denoting the coat front structure. The section 3, which borders around and lies between the sections 2 is also composed of the same weft threads 5 and 6, but in order to render the same more 110

flexible and pliable, the weft threads 6 will skip over and under a plurality of warp threads 4, usually from three to ten warp threads, depending upon the flexibility desired. In the drawings, 5 four warp threads have been skipped. The weft threads 5, which are soft are woven over and under each thread to the warp. The weft section within the bracket B shows two coat front structure sections 2, spaced apart by the flexible section 3 and enough flexible section is provided to 10 permit of easy cutting. When cut out from a length of fabric, the coat front structure 2 will be surrounded by an edging including some of the weft section 1 and some of the weft section 3 15 and part of the weft section 3 which is cut out may constitute the lapel structure, which is customarily more flexible or pliable than the coat front structure per se. Therefore, it will be seen that the coat front structure is formed while the weft 20 section B is being woven, and that it is made stiffer than the surrounding more flexible and pliable section.

When introduced into the coat, this form of coat front structure lies flat; it presents no definite edges between the stiffer sections and more flexible sections, and when ironed, presents no obstacles such as are common with the structures employed in the prior art.

Furthermore, when a tailor purchases a bolt 30 of the fabric, made in accordance with the teachings of this invention, he has everything in one bolt. He has dispensed with the usual bolt of coat front material and with the bolt of hymo or haircloth material, thereby effecting a saving of 35 money.

It is preferred to use resilient wool weft threads for the stiffening threads but horse hair or goat hair threads have been used with an equal measure of success in weaving, the only objection that 40 some tailors have to hair material being the tendency of the hairs to work out of the fabric, in time. In some cases, according to requirements, it has been found necessary to twist together both cotton or linen or jute threads and the 45 resilient wool or animal hair, to form the weft or filling in the portions requiring stiffening.

I claim:

1. As a new article of manufacture, a woven 50 interlining fabric having a continuous warp of soft threads, a plurality of sections of weft of soft threads, a plurality of sections of weft of soft threads and relatively stiffer threads alternating with said first mentioned weft sections, said second mentioned weft sections having a plurality of definitely stiffer sections spaced apart by definitely flexible sections, which are adapted 55 to be cut to form an interlining having a stiff

central body portion with flexible edges surrounding the same.

2. As a new article of manufacture, a woven 80 interlining fabric having a continuous warp of soft threads, such as cotton threads, a plurality of sections of weft of soft threads, such as cotton threads, a plurality of sections of weft of soft threads, such as cotton threads, and relatively stiffer threads such as horsehair alternating with said first mentioned weft sections, said second mentioned weft sections having a plurality of definitely stiffer sections spaced apart by definitely flexible sections, which are adapted 85 to be cut to form an interlining having a stiff central body portion with flexible edges surrounding the same.

3. As a new article of manufacture, a woven 90 interlining fabric having a continuous warp of soft threads, such as cotton threads, a plurality of sections of weft of soft threads, such as cotton threads, a plurality of sections of weft of soft threads, such as cotton threads, and relatively stiffer threads such as resilient wool threads, alternating with said first mentioned weft sections, said second mentioned weft sections having a plurality of definitely stiffer sections spaced apart by definitely flexible sections, which are adapted 95 to be cut to form an interlining having a stiff central body portion with flexible edges surrounding the same.

4. For use in wearing apparel, a stiffening 100 interlining cut from a woven fabric having a continuous warp of soft threads, a plurality of sections of weft of soft threads, a plurality of sections of weft of soft threads and relatively stiffer 105 threads alternating with said first mentioned weft sections, said second mentioned weft sections having a plurality of definitely stiffer sections spaced apart by definitely flexible sections, which are adapted to be cut to form an interlining having a stiff central body portion with flexible edges surrounding the same.

5. A coat front structure consisting of a piece 110 of woven fabric comprising integral body and lapel portions, cut from a woven fabric having a continuous warp of soft threads, a plurality of sections of weft of soft threads, a plurality of sections of weft of soft threads and relatively stiffer 115 threads alternating with said first mentioned weft sections, said second mentioned weft sections having a plurality of definitely stiffer sections spaced apart by definitely flexible sections, said body portion being the stiff section 120 of the second mentioned weft section, and said lapel portion being included in the flexible section of the second mentioned weft section.
